DESIGN FOR A DRESS

Margaret Michelson, New York, N. Y.

Application December 30, 1938, Serial No. 82,084

Term of patent 3½ years

To all whom it may concern:

Be it known that I, Margaret Michelson, a citizen of the United States, residing at 525 Seventh Avenue, New York, in the county of New York and State of New York, have invented a new, original, and ornamental Design for a Dress, of which the following is a specification, reference being had to the accompanying drawing, forming part thereof.

Fig. 1 is the front view of a dress showing my design.

Fig. 2 is the back view of the dress.

The characteristic feature of my design resides in the combination on the specific high waisted, lace dress disclosed of the specific net inserts on the sides of the skirt in the front and back and terminating at the natural waistline, in association with the gathered bodice as shown.

I claim:

The ornamental design for a dress, substantially as shown and described.

MARGARET MICHELSON.
